UNITED STATES PATENT OFFICE

ARTHUR B. MODINE, OF RACINE, WISCONSIN, ASSIGNOR TO MODINE MANUFACTURING COMPANY, OF RACINE, WISCONSIN, A CORPORATION OF WISCONSIN

AIR CONDITIONING DEVICE

Application filed May 28, 1926. Serial No. 112,378.

My invention relates to air conditioning devices and particularly to heating devices having means for moistening the air.

The invention has among its other objects 5 the production of devices of the kind described which are convenient, compact, durable and efficient.

A particular object of the invention is to provide household heating apparatus of simplified construction, which apparatus is adapted to heat and moisten the air and is easily regulated.

Many other objects and advantages of the 10 construction herein shown and described will be obvious to those skilled in the art from the disclosure herein given.

To this end my invention consists in the novel construction, arrangement and combination of parts herein shown and described, 15 and more particularly pointed out in the claims.

In the drawings, wherein like reference characters indicate like or corresponding parts:

Fig. 1 is a front elevation of an air conditioning device embodying the invention;

Fig. 2 is a section taken on line 2—2 of Fig. 1;

Fig. 3 is a section taken on line 3—3 of Fig. 1;

Fig. 4 is a section taken on line 4—4 of Fig. 1;

Fig. 5 is a front elevation of air conditioning apparatus embodying another form 35 of the invention;

Fig. 6 is a section taken on line 6—6 of Fig. 5; and

Fig. 7 is a section taken on line 7—7 of Fig. 5.

Referring for the present to Figs. 1 to 4, inclusive, wherein I have shown an air conditioning device embodying a preferred form of the invention, the reference character 40 10 designates generally a housing adapted to be positioned upon a floor of a room or the like, the housing 10 being preferably provided with legs 11 and being preferably closed at its upper end by a removable closure member or cap 12. As best shown in Fig. 2, the lower end of the housing 10 is open

to the atmosphere and the front wall 14 of the housing is provided with an opening 16 in which a grill 17 or the equivalent is mounted. Disposed in the lower end of the housing is a radiator core 18 which is preferably 55 of the type more fully shown and described in my copending application Serial No. 112,376 filed May 28, 1926. Briefly, the radiator core 18 preferably comprises spaced tanks 19 and 20 which communicate with each other through a plurality of thin walled tubes 21 provided with fins 22, the tanks 19 and 20 being connected by reinforcing side bars 24. In this instance the radiator core 18 is shown operatively connected to pipes 60 26 and 27 which form part of a hot water system but it is obvious to those skilled in the art that the radiator core 18 may be readily connected to a steam heating system. A damper 29 is fixed to a shaft 30 journaled in a bracket 31 mounted upon the radiator core, means comprising a knob 32 being provided for angularly displacing the damper 29 around the longitudinal axis of the shaft 30 to control the flow of air through the 65 housing 10.

Mounted in the upper end of the housing 10 is a tank 34 or the equivalent which is preferably provided with an inclined arcuate bottom wall 35 to permit the tank to hold 70 a relatively large amount of water, it being obvious that with this construction air may flow upwardly through the housing and be discharged therethrough from the lower portion of the grille 17 and other currents of air may flow upwardly through the housing around the tank 34 and then be discharged 75 from the housing through the upper portion of the grille 17. The tank 34 is preferably secured to the end walls 37 of the housing 10 by rivets 38 and tubular spacing members 39, the tank being preferably provided with bracket members 40 to insure that it will be spaced from the front and rear walls of the 80 housing.

The operation of the above described device is substantially as follows: Assuming 85 that the radiator core 18 is operatively connected to a hot water system and that the tank 34 holds a quantity of water, the damper 90 30

29 may be angularly displaced into a position wherein it permits air to flow upwardly through the core and then through the housing to the opening 16 where it passes from the housing. The air, of course, will be heated as it passes through the radiator core 18 and a portion of this heated air will pass through the lower portion of the grille 17 without coming in contact with the water contained in the tank 34. Other portions of the heated air will pass upwardly around the end rear walls of the tank 34 and then over the top thereof to be discharged through the upper portion of the grille 17. The air passing over the tank 34 will evaporate water from the tank and its relative humidity will be raised so that comfortable conditions will obtain in the room. The temperature of the room may be regulated by adjusting the damper 29, it being obvious that when the damper is in its fully open position there will be an efficient exchange of heat between the hot water and the air passing through the radiator core and when the damper is in an intermediate position a reduced quantity of air will flow through the housing, thus decreasing the efficiency of the radiator core. If the damper 29 is moved into its closed position, substantially no air will flow through the housing and the air in the room will not be heated to any great extent. The tank 34 may be refilled at any time, it being only necessary to remove the closure member 12 so that water may be poured into the tank. It will be noted that the closure member 12 is preferably formed with a dead-air space or chamber 12a so that the upper surface of the cap will remain relatively cool at all times.

40 Referring now to Figs. 5 to 7, inclusive, wherein I have shown apparatus embodying another form of the invention, the reference character 45 designates a wall built to provide a recess or chamber 46 which is closed by a plate 47, the plate 47 being provided with upper and lower openings 48 and 49, respectively, which are closed by grilles 48a and 49a, respectively. Disposed in the lower end of the chamber 46 and immediately above the opening 49 is a radiator core 51 which is substantially identical in construction with the aforementioned radiator core 18, the radiator core 51 being operatively connected to pipes 53 and 54 which form part of a hot water heating system. The radiator core 51 has a damper 55 pivotally mounted thereon, the damper 55 being substantially identical with the aforementioned damper 29 and being manually adjustable by means comprising a knob 56. When the damper 55 is in its fully open position or is in an intermediate position air may enter the chamber 46 by way of the aperture 49 and be discharged from the chamber by way of the aperture 48, the air being induced to flow in this direc-

tion by the radiator core 51. Disposed in the upper end of the chamber 46 is a tank 59 mounted upon brackets 60 which are, in turn, mounted upon the plate 47. In this instance, the tank 59 is rigidly secured to the brackets 60 by rivets 62 and the brackets are rigidly secured to the plate 47 by rivets 63. It will be noted that air may flow upwardly in the chamber and pass through the aperture 48 without passing over the tank 59 and that other currents of air may flow around the tank and pass from the chamber through the upper portion of the aperture 48. It is, of course, understood that the tank 59 is adapted to hold a quantity of water which will be evaporated by the air passing thereover and the relative humidity of the air will be raised.

Means is provided whereby the tank 59 may be filled with water, this means preferably comprising a trough or spout 65 slidably journaled in an aperture 66 formed in the plate 47, the aperture 66 being so positioned that the inner end of the spout is positioned directly over the tank 59. The outer end of the spout or trough 65 is preferably closed by a disc 68 or the equivalent which also serves as a closure member for the aperture 66 when the spout or trough is disposed in a position wherein it is shown in full lines in Fig. 6. When the tank 59 is to be filled the spout or trough 65 is preferably moved into the position wherein it is shown in dotted lines in Fig. 6 and water is poured into the outer end thereof.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. In air conditioning apparatus, a radiator core, an enclosure for said core, a tank fixedly positioned in said enclosure for holding a supply of water, and a member projecting into said enclosure having an end adapted to be moved relatively to the casing to expose an end of said member to discharge water into said tank when water is poured into said end of said member.

2. In air conditioning apparatus, a radiator core, an enclosure for said core, a tank positioned in said enclosure for holding a supply of water, and a member slidably mounted in an aperture located above said tank, said member projecting into said enclosure and adapted to discharge water into said tank when water is poured into the end of said member.

3. The combination with a wall having a recess therein, of a radiator core mounted in

5 said recess, a plate for closing said recess, said plate being provided with upper and lower openings whereby a current of air may flow through said recess, and a tank for holding water carried entirely by said plate, said tank being disposed in said recess and extending across one of the openings in said plate.

10 4. In air conditioning apparatus, an enclosure, a radiator core disposed adjacent the bottom thereof, a damper mounted on said radiator core and above the same, means extending outside of said enclosure for manipulating said damper, and a tank mounted 15 in said enclosure above said radiator core, said enclosure having openings adjacent the top and bottom thereof for the passage of air, and said tank having a wall which extends from adjacent one edge of the top opening to the opposite edge of said opening.

20 5. In air conditioning apparatus, an enclosure having a front plate, a radiator core disposed in said enclosure, a damper mounted on said radiator core and above the same, means extending outside of said enclosure for manipulating said damper, and a tank, the bottom wall of said tank extending from said wall to adjacent the rear edge of said radiator, said tank being carried entirely by said front plate and disposed over said radiator core, said front plate having an opening below said radiator core and an opening in the upper part thereof.

25 6. In a device of the class described, a cabinet having a wall with an opening in the upper part thereof, a heating unit having spaced apertures forming the bottom wall of said cabinet, humidifying means mounted within said cabinet serving also to deflect a current of air outwardly through said opening, and means mounted in said cabinet for regulating the volume of air passing therethrough, said humidifying means being so arranged that a portion of the air passing upwardly 30 from said unit will move over the top of said humidifying means so as to carry moisture out of said cabinet.

45 7. In air conditioning apparatus, a radiator core, an enclosure for said core, a tank mounted in said enclosure above the core, said enclosure having openings at the top and bottom thereof for the passage of air, said tank being extended across the top opening and having a wall projecting from the rear wall 50 of the casing in an upward direction toward the upper edge of the opening.

8. In air conditioning apparatus, a radiator housing having substantially vertical walls, said housing being provided with an opening 60 in its bottom and with an opening adjacent the upper end of one of its vertical walls, a radiator core disposed at the lower end of the housing, a tank for holding water disposed in the upper end of the housing, said tank 65 having a wall, an edge of which is arranged

adjacent the upper edge of the opening and having an edge arranged in spaced relation to the rear wall of the casing and located adjacent the lower edge of said opening.

9. In air conditioning apparatus, a radiator 70 housing having an opening in the opposite ends thereof and having a water tank located in the upper end of said housing, the tank having an arcuate wall which is of a continuous curve from the front to the rear of the 75 tank.

10. In air conditioning apparatus, a radiator core, an enclosure for said radiator core having upper and lower openings whereby a current of air may flow through said core, 80 and a tank for holding water, said tank having a wall projecting toward said core and providing means for directing air toward the opening, positioned intermediate the upper and lower ends of said upper opening so that a portion of said air will flow over said tank, and another portion will flow beneath the tank directly to said upper opening.

11. In air conditioning apparatus, a radiator core, an enclosure for said radiator core 90 having upper and lower openings, a tank for holding water positioned intermediate the upper and lower ends of said upper opening, said tank having a wall thereof extending from adjacent one edge of said opening toward the 95 opposite edge of the opening and rear wall of the enclosure.

12. In air conditioning apparatus, a radiator housing having substantially vertical walls, said housing being provided with an opening 100 in its lower end and with an opening adjacent the top of one of its vertical walls, a radiator core disposed in said housing below said upper opening, a tank mounted in said housing intermediate the upper and lower ends of said upper opening, the rear wall of said tank being of a greater dimension than the front wall thereof, said tank being of smaller cross-sectional area than the housing whereby air may flow from the core and over the housing and thence through said upper opening and the remainder of the air may flow underneath said tank directly to said upper opening.

110 In testimony whereof, I have hereunto 115 signed my name.

ARTHUR B. MODINE.
